CARTON STRUCTURE

Andrew E. Bueschel, Mokena, Ill., assignor, by
mesne assignments, to Consolidated Carton,
Inc., Chicago, Ill., a corporation of Illinois

Application August 1, 1936, Serial No. 93,757

11 Claims. (Cl. 229—29)

The present invention relates to collapsible cartons and in particular to a construction within the carton to provide either a false wall or bottom, a partition, or a false wall and a partition perpendicular thereto. It has particular application to egg cartons wherein a partition is provided to separate two rows of eggs, and wherein the false wall is a bottom to provide a cushion for the eggs.

The invention in its preferred form is adapted to the standard type of egg carton wherein two long rows of six eggs each are separated by a partition to provide "dozen" sized boxes. Therefore, the invention will be specifically illustrated and described by reference to egg cartons, but in such a way as to indicate how the invention may be differently embodied and modified for many special cartons.

The 12-egg carton is provided on the market by many forms of chip-board or cardboard material. Each box is formed from sheet material, folded and glued, so as to be collapsed to a flat form. The user must set up the box to receive eggs. It is the aim in the art to simplify the set-up operation without complicating the manufacture and without increasing the expense of the box. To balance economies constructions have been provided which require several manipulations to set up the box. Sometimes one or more partitions accompany each major box, to be used in the set-up operation for completing the structure of the box.

The present invention may be embodied to provide a box for eggs which needs but one simple operation to set up the box to receive eggs, and the act of inserting the eggs may effect such additional operations on parts of the box structure as are necessary to make it a fixed set-up box. The collapsed box of the present invention is merely opened from a flat form to a box form, presenting compartment areas for eggs, and then the eggs are inserted. The box is, therefore, termed a "self set-up" box, which term will be appreciated for egg cartons and other cartons from the following explanation.

The object of the invention is to provide structure having linkage connections capable of folding flat with the box proper and of being operated automatically by the act of opening the collapsed box, to bring into position a partition or false wall or bottom structure, or both.

A particular object of the invention is to provide an egg carton complete in all essential parts, without separate parts, from one continuous sheet of material, and foldable flat.

Various other and ancillary objects and ad-

vantages of the invention will become apparent from the following description and explanation of the invention as given below in reference to the illustrative forms of the accompanying drawings, in which:

Fig. 1 represents a single sheet or blank, cut and scored for folding into the eggs carton of Fig. 2.

Fig. 2 is a perspective view of the collapsible carton formed by folding and gluing the blank 10 of Fig. 1.

Fig. 3 is a fragmentary view of a folding box having a false wall, a support therefor, and a partition, illustrating a structure not of one sheet, and also a non-inclined false wall.

Fig. 4 is an exemplary form showing several embodiments of the invention in a structure differing in use from an egg carton.

Briefly anticipating the detailed structure for an egg carton, the box in its preferred form is 20 made from a single flat blank which is cut and scored, then folded and glued, to provide every necessary part of the carton. The completed box exhibits individual side-by-side compartments for eggs, a closed bottom, a cover, and a false bottom 25 to cushion the eggs. In addition the box may be so made that it can be divided at predetermined places to provide two or more boxes, each as complete as the parent in the above mentioned respect, except that each may be lacking in 30 divisibility like the parent. The structure is such that the false bottom may be supported between the box sides, by them and by the bottom, and be integral with a longitudinal partition. Furthermore, the intersection partitions and false 35 bottom which provide egg compartments are all capable of being formed from the one continuous flat blank, and of being housed in the box shell proper, which is also capable of being a continuous part of the same blank.

Referring to both Figures 1 and 2 and largely for directions of parts to Fig. 2, the egg carton has an outer shell and an inner shell, the latter having top and bottom spaced respectively from the top and bottom of the outer shell. The 45 outer shell consists of cover 10 with edge flap 11 having hooked projections 12 which lock into structure later described. The cover 10 continues as box side 13, then as box bottom 14, then as box side 15. The inner shell then begins as a series 16 of elements crossing the open top of the box which elements provide ties and cross partitions. The series 16 of elements is formed from a continuation of the sheet of box side 15, and then continues as a reinforcement 50

55

17 of side wall 13, to which it is secured as far as the scored folding line 18. The sheet now begins to form the false bottom, which is in two longitudinal sections in the present instance. The 5 first section is designated 19 and inclined downwardly at a slight angle to the scored folding line 20 from which a short strip 21 of the sheet goes down to touch the bottom 14 and then upon folded edge 22 it reverses upon itself with 10 adhesive union to project upwardly as a web 23 parallel to the box sides 13 and 15. The web extends to a folded edge 24 where it reverses again upon itself with adhesive union. The length of web 23 between the folding lines 22 15 and 24 is greater than the distance between the box bottom 14 and the top 16 of the inner shell, but the web 23 is cut into fingers 25 and intervening spaces 26 which cooperate with the series 16 of tie elements so that there is no obstruction 20 as will later appear. The reversing part of the sheet from folding line 24 forms a reinforcement strip 27 for part of web 23 to the scored folding line 28, which is located on web 23 higher from the bottom than scored folding line 20 25 on the opposite side of the web 23.

From line 28 the sheet inclines slightly upwardly forming another section 29 of false bottom as far as the scored folding line 30, beyond which the remaining strip 31 of the sheet is 30 secured to the box wall 15.

All the scored horizontal lines are indicated by arrows at the right of Fig. 1. All the areas of the sheet employed are indicated at the left of Fig. 1.

35 Beginning at the top of Fig. 1, the horizontal scored folding lines not above specifically designated are numbered downwardly in the drawings for the purposes of reference: 32, 33, 34, 34a, 34b and 34c.

40 The false-bottom sections 19 and 29 are intended to support the eggs above the outer shell bottom 14. They may be punched to provide recesses for ends of the eggs and to cushion the eggs in said recesses. Numerous forms of cushion structures are known and may be used. Herein 45 there are illustrated the type shown in my earlier Patent No. 1,940,292, issued Dec. 19, 1933. The recesses are designated generally by the numeral 35. Twelve egg recesses are formed in rows 2 x 6. 50 The carton is made conveniently divisible into two sections each 2 x 3, and for this purpose the blank sheet is perforated at suitable places to permit easy breaking or cutting. A knife may be used. To insure ease in severing the sections, it is preferred that the inner pieces which 55 are not part of the outer shell, or adhesively united to it, be already severed. Hence the perforated portion along the middle division line in Fig. 1 is partly a dashed line 36 or 38 in strip 60 31 to indicate perforations, and partly a full line 37 to indicate completed cutting in advance of assembling the box from the blank. The arrangement may be varied as desired.

65 It is to be noted that the perforations 38 in strip 31, at the end of the blank, serve to hold the blank in its rectangular form, the cut line 37 tending to make a bifurcated blank out of the whole.

70 The series 16 of elements above briefly referred to are made to form several cross top ties 40 and 41 at the ends of the carton, and at the middle adjacent ties 42 and 43 at the line of division. These ties remain flat across the top of the carton and carry the respective flaps 44, 45, 46 and 75 47 which can be bent down on the respective

scored lines indicated as dotted lines 48, 49, 50 and 51. The ends of these flaps are defined by an obtuse-angular cut with one line 52 (see flap 44) between the flap and tie (see tie 40) and the other line 53 between the flap and the section 15 or 17 as the case may be.

Various portions of the section 16 are cut out to define the above mentioned ties and flaps, and also a number of intermediate flaps which function as vertical ties and cross partitions shown 10 from left to right by the numerals: 54, 55, 56 and 57. Each of these is carried near its ends and at one edge by triangular tabs such as those numbered 58 and 59 on tie-flap 54, with dotted lines 60 and 61 indicating scored folding lines continuous with edge 62 of the tie-flap. The ends of the tie-flaps are severed from the wall sections 15 and 17 by the respective cuts 63 and 64 (see Fig. 1).

The four triangular tabs 58 above described 20 are like tabs formed on the flat-ties 40 and 43, which tabs are numbered 65 and 66 at the front wall adjacent wall section 15. These provide catches for locking the cover. On the projections 12 of the cover flap 11, there are hooks or 25 tabs 67 which are readily cammed inwardly by the triangular tabs and then locked under them.

From the foregoing description and directly 30 from Fig. 2, it can be readily appreciated that the fingers 25 on the longitudinal partition can project above the level of the ties or cross partitions and between them. The recesses 26 in the longitudinal partition may be made curved to accommodate the path of the various flaps as they are turned from horizontal to vertical position, some 35 being shown as turned. At the ends of the carton, and at the middle of the division line of the carton, the fingers 70 and 71 at the carton ends, and the adjacent or divisible fingers 72 and 73 at the center, are shorter to terminate below 40 the respective flat ties 40, 41, 42 and 43.

The parts above described are arranged in a novel way for the particular carton illustrated so that on severing the carton, one half-carton will substantially duplicate the other, and so 45 that each half-carton will be complete in providing complete compartments for the eggs at the division line. Each half-carton is similarly locked in closed position by three hooks, and in the whole carton, these all move in the same 50 direction to lock or to unlock them.

In collapsing the carton from the position shown, the front wall 15 moves forward in Fig. 2 along the line of dotted arc-arrow 68. The bottom 14, sides 13 and 15, and the ties of series 16 55 provide a parallelogram linkage. The false bottom sections 19 and 29, being nearly parallel with the bottom 14, but being free from linkage to the bottom at the web or vertical partition 23, readily follow in the collapsing movement and lie flat. 60 The spaced axes 20 and 28 where the false bottom sections hinge on the web 23 cause the web to be inclined forwardly and to lie flat.

On setting-up the box the reverse motion causes the mid-web or partition 23 to be tilted 65 toward the vertical without special effort to raise it. It may not always go to the exact vertical position, but it can easily be pushed to it by the end of an egg on insertion. The eggs are also used to bend the flaps down to serve as cross- 70 partitions and thus to hold the box in rectangular form against collapsing.

It is particularly to be noted that the inclined floor width dimensions are greater than the same box-bottom dimensions. This serves to hold the 75

mid-web down against the box bottom as a sort of force acting beyond a dead-center. This is not necessary in the particular box described, where the short fingers underlie the flat ties to insure holding the mid-web down to the bottom when no eggs are in the carton. Therefore, the false-bottom sections could be made parallel with the true bottom. Also the vertical spacing of axes 20 and 28 could be omitted, but the tilting force on the web would be greatly reduced or even lost.

As an additional and optional structure, means may be provided on one or both sides of the web or partition to lock the same in a vertical or other required position. These may consist of tabs punched in the stock to be bent into locking position.

Two exemplary forms are shown at 75 and 76, bending respectively on scored folding lines 77 and 78. Other forms may be readily made as will be appreciated by those skilled in the art. Although these are shown in the bottom 14 of the outer shell, they could be formed elsewhere, as in a transverse partition. A thumb-hole form is also shown having two adjacent right triangles 79 each bending on the hypotenuse.

The above described carton is an example of the present invention embodied in a one-piece unit. Of course, a carton of similar form may as well be made from several pieces. Likewise the carton is an example of both a false wall, a support therefor, and a partition. Obviously the back-to-back sections 21-23, which as a single web support the false bottom, could be omitted, and the partition 23-27 above it retained, or vice versa, without departing from the invention here set forth. One or more false bottom supports or upper partitions may be made, and they need not be at the same location.

Furthermore, the recesses illustrated for eggs may be made much larger and be merged in such a way that the false bottom is practically eliminated, leaving only linkage connections somewhere, preferably at the ends, to support and to operate the partition on opening the box. These modifications are indicated in Fig. 3 and Fig. 4, and these may better illustrate the principle operating in the egg carton.

In Fig. 3 the walls 80, 81 and 82 represent any three continuous faces of a collapsible box hinging on lines 83 and 84. A partition 85 is provided parallel to walls 80 and 82, but the partition has its edge 86 free. A linkage connection 87 extends between the partition 85 and wall 82, above the level of wall 81, but closely parallel to it. This connection is shown as having a narrow width and as not providing a complete false wall. Its function is primarily one of linkage for motion and for support. It hinges on lines 88 and 89, parallel to lines 83 and 84. A wall-forming linkage connection 90 is shown between wall 80 and partition 85, at a lower level than linkage 87, hinging on axes 91 and 92. Because of the different leverages produced by the locations of the axes, the linkage 87 moves faster than linkage 89 in moving the structure to collapse or set-up the box. Hence, the partition 85 is bound to be tilted or moved. The degree and direction of tilting may readily be controlled by the positioning of the axes and the linkage connections.

In Fig. 4 there is shown a false wall structure with several vertical supports therefor which are not secured to the true wall. The structure is generally the same as in Fig. 3, except that the several false wall sections are inclined to move

beyond a dead center. Folding box walls 93, 94 and 95 have a one-piece insert comprising securing strip 96 on wall 93, scored line 97, false wall 98 inclined toward wall 94, scored line 99, a supporting section reversed on itself as at 100, 5 scored line 101, above line 99, downwardly inclined false wall section 102, scored line 103, reversed portion 104 forming another supporting strip, which continues as in the egg carton to provide a vertical partition 105, scored folding 10 line 106 above line 103, upwardly inclined false-wall section 107, folding line 108, a third vertical partition 109, folding line 110, above line 108, the last false-wall section 111, folding line 112, and a securing strip 113. 15

The total of the widths of the false wall sections is greater than the width of the box-wall 94, so that the inner structure may be lifted to an upper position, the edge of which is indicated by dotted line 114. To move from full-line position to dotted-line position, a sort of "dead center" is passed through. This structure gives a snap and force to the inner structure to move it and to hold it in the full-line position indicated. This structure makes it unnecessary to 20 anchor the supporting webs against the true-wall. 25

In the egg-carton of Fig. 1 and Fig. 2, where the short fingers 10, 11, 12 and 13 underlie the respective flat cross ties 40, 41, 42 and 43, the 30 structure forces the false wall toward the bottom and prevents it rising above the dead-center, unless the vertical partition be tilted to prevent its fingers forcing the inner structure downwardly. 35

Referring to Fig. 2 (and Fig. 1) it is also to be considered that the invention contemplates the disclosed type of compartment-forming inner structure for any box, whether the box be folding or rigid. Such compartmentizing structure 40 may be collapsible, but the ability to make it in open flat form of one or more pieces is an important feature. It need not necessarily be glued as described. Flat cut blanks may be folded on scored folding lines to produce several transverse partitions and one or more supporting webs where there is also introduced a false-wall, and one or more vertical partitions. Consider, for example, the portion of the blank of Fig. 1, beginning with section 15, and extending at least 45 to folding line 24 at the top of the fingers, or even to the end section 31. The variations above described may be introduced. If the blank is taken to include sections 15 to 31, then it may be folded into a rectangular insert to give the 50 desired structural insert. Section 31 may be widened to terminate with section 15 at the bottom of a box into which the structure is inserted, thus to avoid adhesive or other securing means as preferred in the egg carton. 55

In the accompanying claims, where the terms "top", "bottom" and "sides" have been used, it is to be understood that these are merely reference words indicative of relations of the parts, and are not compelling in the use of the box as 60 particularly claimed. The claims also contemplate structures containing the exemplary modifications discussed, as well as others, which may be made without departing from the spirit and scope of the invention. 65

I claim:

1. A folding carton structure comprising a box having a bottom with parallel spaced edges, box sides hinged at said edges, a partition member to lie between said box sides and capable of rest- 70

ing on the bottom, a linking connection hinged at both ends above said bottom at the partition member and at one of said sides, and a second linkage connection hinged at both ends above 5 said bottom at the partition and at the other side, the hinging axes of said connections at the partition being parallel and spaced apart in the direction of the partition, whereby said connections serve to move and to support the partition 10 member between the two sides.

2. A folding carton structure comprising a box having a bottom with parallel spaced edges, box sides hinged at said edges, a partition member to lie between said box sides and capable of resting 15 on the bottom, a linking connection hinged at both ends above said bottom at the partition member and at one of said sides, a second linkage connection hinged at both ends above said bottom at the partition and at the other side, 20 the hinging axes of said connections at the partition being parallel and spaced apart in the direction of the partition, whereby said connections serve to move and to support the partition member between the two sides, and locking means 25 associated with the bottom to hold the edge of the partition member immovable on the bottom.

3. A folding carton structure comprising a box having a bottom with parallel spaced edges, box sides hinged at said edges, a partition member 30 to lie between said box sides and capable of resting on the bottom, a linking connection hinged at both ends above said bottom at the partition member and at one of said sides, and a second linkage connection hinged at both ends above 35 said bottom at the partition and at the other side, the hinging axes of said connections at the partition being parallel and spaced apart in the direction of the partition, whereby said connections serve to move and to support the partition 40 member between the two sides, one of said connecting linkages being extensive in sheet-like form to provide an area of false bottom for the box.

4. A folding carton structure comprising a box 45 having a bottom with parallel spaced edges, box sides hinged at said edges, a partition member to lie between said box sides and capable of resting on the bottom, a linking connection hinged at both ends above said bottom at the partition member and at one of said sides, and a second linkage connection hinged at both ends above 50 said bottom at the partition and at the other side, the hinging axes of said connections at the partition being parallel and spaced apart in the direction of the partition, whereby said connections serve to move and to support the partition member between the two sides, one of said two linkage connections being inclined upwardly from the partition to the box side, whereby to provide 55 a force against removal of the partition edgewise away from the bottom.

5. A folding carton structure comprising a box 60 having a bottom with parallel spaced edges, box sides hinged at said edges, a partition member to lie between said box sides and capable of resting on the bottom, a linking connection hinged at both ends above said bottom at the partition member and at one of said sides, and a second linkage connection hinged at both ends above 65 said bottom at the partition and at the other side, said connections serving to move and to support the partition member between the two sides, said two linkage connections being hinged at the partition on parallel axes spaced apart in 70 the direction of the partition, and extending up-

wardly to the box sides, whereby to give direction to the partition and an urge to off-center position in the normal spacing of the box sides.

6. A folding box comprising a bottom, parallel opposite box sides hinged to said bottom, and a unitary structure inside the box forming a false bottom and a support therefor both of which are foldable flat with the box, said structure consisting of a continuous sheet of foldable material providing two outer sections secured to the 10 box sides and folded to provide hinging axes at the box sides above the level of the box bottom, each outer section having an adjacent portion extending from its axis towards the middle of the box to provide false bottom sections for the 15 box, the portion of the sheet between said false bottom sections being reversely bent forming two parts united to each other to provide a web running toward the box bottom for supporting the false bottom and being hinged related to said 20 false bottom sections by folds in the material providing axes at different heights on said web.

7. A folding box comprising a bottom, parallel opposite box sides hinged to said bottom, and a unitary structure inside the box forming a false bottom and a support therefor both of which are foldable flat with the box, said structure consisting of a continuous sheet of foldable material providing two outer sections secured to the box sides and folded to provide hinging axes at 30 the box sides above the level of the box bottom, each outer section having an adjacent portion extending from its axis towards the middle of the box to provide false bottom portions for the box, the portion of the sheet between said false 35 bottom sections being reversely bent forming two parts united to each other to provide a web running toward the box bottom for supporting the false bottom, and a continuation of said web as a partition above the false bottom sections, said 40 web being hinged related to said false bottom sections by folds in the material providing axes at different heights on said web.

8. A cushioned carton including a cover and transverse and longitudinal partitions made 45 from a continuous sheet folded and glued to form inner and outer shells, the walls constituting the bottom of said shells being spaced apart, the top wall of the inner shell being cut to produce flaps adapted to be folded down to serve as transverse 50 partitions, the top wall of the outer shell being free along three edges to form a cover that may be opened and closed, and the bottom of the inner shell being folded upon itself twice to form vertical longitudinal webs one above and one below the bottom of the inner shell, respectively, to partition the carton, and to support the bottom of the inner shell on and above the bottom of the outer shell.

9. A cushioned carton including a cover and transverse and vertical partitions made from a continuous sheet of material folded and glued to form inner and outer shells, the walls constituting the bottom of said shells being spaced apart, the top wall of the inner shell being cut 65 to provide plane cross ties and flaps adapted to be folded down to serve as transverse partitions, the top wall of the outer shell being free along three edges to form a cover that may be opened and closed, and the bottom of the inner shell being folded upon itself to form a longitudinal supporting web extending to the bottom of the outer shell, and being further folded upon itself to form a longitudinal web above the bottom of the inner shell, said last-mentioned web being cut 70

- to provide fingers to support the plane cross ties.
10. An interior structure for a box for providing compartments therein made from a continuous sheet of material folded to form a series of adjacent sheet sections, one section of material to be on one side of the box, a second section to cross the opening of the box, said section being cut to produce flat cross ties and flaps to be folded down as transverse partitions, a third section to lie on the opposite side of the box, and a fourth section to reside below the second section and across the opening of the box, said fourth section having an intermediate portion thereof folded upon itself twice to form vertical longitudinal webs, one above and one below the general level of the said fourth section, the upper web serving as a longitudinal partition extending from the fourth section toward the second section, and the lower web serving as a support for the said fourth section.
11. An interior structure for a box for pro-

viding compartments therein made from a continuous sheet of material folded to form a series of adjacent sheet sections, one section of material to be on one side of the box, a second section to cross the opening of the box, said section being cut to produce flat cross ties and flaps to be folded down as transverse partitions, a third section to lie on the opposite side of the box, and a fourth section to reside below the second section and across the opening of the box, said fourth section having an intermediate portion thereof folded upon itself twice to form vertical longitudinal webs, one above and one below the general level of the said fourth section, the upper web serving as a longitudinal partition extending from the fourth section toward the second section, and the lower web serving as a support for the said fourth section. 10
